MULTISTAGE AMPLIFIER OR RECEIVER ARRANGEMENT

Application filed November 5, 1927, Serial No. 231,224, and in Germany November 26, 1926.

The object of the present invention is an amplifier or receiver circuit arrangement comprising a plurality of tubes, which is particularly suited for being supplied from a power supply line. It is known that, according to former practice, it has been necessary in schemes of the said kind to heat the first tubes at least from separate batteries as otherwise the frequency of the supply line would manifest itself in an inconvenient and disturbing manner in the output circuit of the amplifier. Hence, feeding from a network was at most practicable or admissible for the end stage only.

Now, the essential feature of the invention consists in that the filaments of the first few tubes are heated by the plate current of the last or power tube or the last few tubes. In an arrangement of this nature, the filament current of the first tubes will not vary any more at the rhythm or frequency of the network or supply current, but only at that of the audio or tonal frequencies to be transmitted, and these frequencies are so high in value that they no longer produce a disturbing action owing to the thermal inertia of the filaments.

For reasons of purity of transmission and avoidance of back-couplings, it is a good plan in circuit arrangements comprising a comparatively great number of stages to eliminate from the heating or filament current of the first tube also the audio-frequency component wholly or partly. A means to this end, for instance, would consist to provide conveniently in series with the filaments of the first tube a sufficiently large condenser to pass through it the a. c. component of the plate current of the end tube or tubes varying during the operation of the amplifier and to thereby preclude the same from the filaments. To promote this action, according to the invention, choke-coils may further be provided in series with the filaments. Another scheme would be to replace the said condenser suitably by a buffer battery.

A still more effective means, according to the present invention, consists in forming the last stage or stages of the tube amplifier

by tubes connected push-pull-fashion or in phase opposition whereby the total plate current flowing through the last stage or stages is made almost independent of the speech or voice currents, seeing that, at a given instant, any increase in the plate current of one tube would correspond to a similar decrease in the plate current of the other tube. The total plate current of the two push-pull tubes is not brought from the filament directly to the negative pole of the potential source or ground, but a better plan is to connect, conveniently in series, the filaments of the first tubes of the amplifier in the path between the cathodes or filaments of the last pair of tubes and the negative pole of the potential source or ground.

To further preclude any chances of the heating of the first tube suffering fluctuations by possibly existent slight variations in the total plate current of the last pair of tubes owing to small differences in these two tubes, the above-mentioned arrangement comprising choke-coils or condenser or buffer batteries may be used also in this case. One advantageous way of practicing this scheme consists in connecting the plate leads by way of corresponding choke-coils with both ends of the filament or the parallel connected filaments of the last tubes, if desired, with the addition of a condenser, with the middle of the secondary winding of the heating-current transformer.

Variations in the total plate current of the last pair of tubes also in the push-pull arrangement, can be eliminated to a certain extent by that a variable resistance is connected, say, in parallel to the grid leak or the discharge path, for the purpose of compensating or neutralizing such differences as may be present in internal resistance, slope, etc.

Another feature of the invention is that the potential fall in the heating circuits of the first or input tubes is used for the purpose of providing grid potential for all or some of the amplifier tubes.

In the drawing:

Fig. 1 shows one embodiment of the invention using a single power tube and

Fig. 2 shows a push-pull arrangement whereby improved action is obtained.

One embodiment of the basic ideas of the invention is shown by way of example in 5 the accompanying drawing Fig. 2 representing a push-pull arrangement for the end tubes. The amplifier is fed from an alternating current supply-line W. The current rectified in a rectifier g, after having passed 10 through a rejector circuit ("noise-killer") s inserted in known manner is fed to the plates of the different tubes. One part of the plate currents is conducted through a leak h and the two halves of the primary winding of a 15 repeater (transformer) u to the two end tubes r₄ and r₅ connected push-pull-fashion, whence it is conducted by way of choke-coils h and f and the series-connected filaments of the first tubes r₁, r₂, r₃ (r₁ being, for instance, 20 an audion tube) to ground or the negative pole of the rectifier g. A sufficiently large condenser c is connected in parallel to all of the filaments, another choke-coil b between the filaments of tubes r₃ and one of the junction 25 points of the condenser c. The last push-pull arranged tubes may be heated by a. c. through a transformer t without any harmful consequences, the two filaments of said tubes being conveniently connected in 30 parallel with the secondary winding of said transformer.

To regulate the grid potentials of the different tubes, the connection of the combined plate and filament leads l to ground contains 35 a resistance v. Furthermore, the grids of the different tubes are not directly connected by way of the secondary windings of the transformers with the corresponding filaments, but with ground. In this manner, the potential fall across resistance v acts as a biasing 40 potential for the different grid circuits. The said resistance v is suitably so proportioned that fluctuations in the total plate current in the joint lead l are nearly eliminated by incidentally produced variations in the grid biasing 45 potentials. In parallel relation to one of the push-pull-connected tubes, say r₅, there is a fine-stepped resistance w, the object of which is to compensate slight discrepancies 50 in the tube constants liable to lead to alterations or fluctuations in the total plate current of the two push-pull-connected tubes upon the flow of speech currents through the amplifier.

55 However, in an arrangement of this kind, it may happen that the plate current of the end tubes fails to suffice for the heating of the preceding tubes.

This inconvenience, according to the present 60 invention, is eliminated by that a suitably variable resistance is connected in parallel to the last amplifier stage, said resistance being so proportioned that a current is caused to flow therethrough which, together with the 65 plate current, results in and furnishes the de-

sired heating current for the preceding tubes. So far as the insertion of the said resistance is concerned, it is immaterial whether the last amplifier stage consists of a single or simple tube or of a combination of push-pull-connected tubes.

Another embodiment of the basic idea of the invention is illustrated in the accompanying drawing Fig. 1. In this scheme, the last stage of the amplifier, r₄, does not consist of 70 a push-pull connection, but rather of a single tube, a variable resistance z being arranged in parallel to the plate discharge path, in order to insure an adequately large heating current for the preceding tubes r₁—r₃. The 75 a. c. taken, for instance, from a network W is rectified by a rectifier g, is then smoothed by choke-coil s and is finally fed through the tube r₄ and resistance z to the preceding tubes r₁—r₃. The fluctuations in the plate 80 current also in this case are precluded from the filaments to be heated by means of choke-coils b, f, and h and a parallel-connected condenser c, the latter being optionally replaced by a buffer battery. The last or end (power) 85 tube may be heated with a. c. by way of a transformer. In case the last stage consists of two push-pull-connected tubes, one of the latter may in addition be provided with a parallel resistance, for the object of regulat- 90 ing its own resistance.

As to the rest, in both cases the circuit arrangement is built up in the usual way. The currents entering at e and to be amplified may be fed or transferred from one stage 100 of the amplifier arrangement to the next either by means of transformer coupling, as shown in the drawing, or else by capacity-resistance coupling, until they reach a. The circuit connection scheme hereinbefore described is useful also in the case of d. c. supply from a network.

Having thus described my invention what I desire to protect by Letters Patent is as follows:

1. In an amplification system, a plurality of interlinked electron tube circuits, each of said tubes having grid, cathode and anode electrodes, and at least one of said tubes having larger power capacity than the others of 115 said tubes, a supply circuit for furnishing the anode potential to all of said tubes, and a filtering circuit, a series circuit comprising the cathode electrodes of the tubes of less power capacity than the last mentioned of 120 said tubes and including the anode electrode of at least one of said tubes of larger power capacity, said supply circuit and said filtering circuit, means including at least one choke coil for connecting said last named 125 cathode electrodes and the cathode electrode of said power tube, and a capacity shunted across said cathode circuit.

2. In an amplification system, a plurality of interlinked space discharge device circuits,

each of said devices comprising a grid electrode, an anode and a cathode, and at least one of said space discharge devices having larger power capacity than the others there-
5 of, a supply circuit for furnishing the anode potential to all of said space discharge de-
vices, and a filtering circuit, a series circuit comprising the cathodes of the space dis-
charge devices of less power capacity than
10 said last mentioned space discharge devices and including the anode electrode of at least one of said space discharge devices of larger power capacity, said supply circuit and said filtering circuit, means including at least one
15 choke coil for connecting said last named cathodes and the cathode of said power tube, a capacity shunted across said cathode cir-
cuit, and a variable resistance shunted across the anode and cathode of said power space
20 discharge device.
